Des. 237,290
Patented Oct. 21, 1975

237,290

GAME BOARD

Piet Hein, Heather Field, Park Road, Stoke Poges,
Buckinghamshire, England

Filed Sept. 24, 1973, Ser. No. 400,021

Claims priority, application Denmark Mar. 23, 1973

Term of patent 14 years

Int. Cl. D21—01

U.S. Cl. D34—5 SS

FIG. 1 is an isometric view of a game board;
FIG. 2 is a plan view of the game board shown in
FIG. 1;

FIG. 3 is a side view along the line 3—3 of FIG. 2;

FIG. 4 is another side view looking in the diametric op-
posite direction from FIG. 3; and

FIG. 5 is a cross-sectional view along the line 5—5
of FIG. 2.

I claim:

The ornamental design for a game board, substantially
as shown.
